UNITED STATES PATENT OFFICE.

ALBERT J. BATES, OF CHICAGO, ILLINOIS.

INSULATING RAIL-FASTENER.

1,083,181.

Specification of Letters Patent. Patented Dec. 30, 1913.

Application filed August 6, 1913. Serial No. 783,231.

To all whom it may concern:

Be it known that I, ALBERT J. BATES, a citizen of the United States, residing at Chicago, in the county of Cook and State of Illinois, have invented certain new and useful Improvements in Insulating Rail-Fasteners, of which the following is a specification.

This invention relates to means for fastening rails to railway ties and particularly to composition ties such as are described in Letters Patent of the United States for railway tie fastening, Number 1,042,309, granted to me on October 22, 1912.

One of the principal objects of the present invention is to provide means for securing the rails to a composition tie in a simple and improved manner so that the rails, when secured in position, will be electrically insulated from each other and also from the earth in which the tie is supported.

As it is well known to railway engineers and others skilled in the art to which this invention belongs it is the custom to utilize the rails to carry an electric current for the operation of the various block systems of signaling at present employed. Where composition ties are used they are ordinarily composed of concrete in which are embedded structural iron reinforcing members, the concrete serving to insulate the rails from each other and from the ground, and from the iron reinforcing members forming a part of the ties. This has been found to efficiently insulate the rail while the concrete is dry but losses of the current have resulted when the tie becomes wet as after a rain. Inasmuch as the current provided to operate the block systems is of exceedingly low potential an escape of any of it into the ground is of extreme importance and likely to result in rendering the signaling systems inoperative.

One of the principal objects of the present invention is to provide in addition to the insulation provided by the concrete an insulation which will prevent the escape of any of the electrical energy when the ties are wet, insuring thereby the continued efficiency of the signaling system employed.

A further object of the invention is to provide means interposed between the composition tie and rail to distribute evenly over the bearing surface of the tie the force of the load carried by the rail preventing thereby any concentration of this force upon

limited areas and the resulting crushing or breaking down of the concrete or other material forming the tie.

Additional objects and advantages of the invention will be apparent as it is better understood from the following description when considered in connection with the accompanying drawing, illustrating a preferred embodiment thereof.

On the drawing: Figure 1 is a partial vertical sectional view taken transversely of the rail and longitudinally of the tie; Fig. 2 is a perspective of one of the thrust plates forming a part of my new and improved fastening device, and Fig. 3 is a partial horizontal sectional view showing certain details of construction of the rail fastening device at one side of the rail.

Referring to the drawing a rail of ordinary construction is shown as secured to a composite tie. The tie in the present instance is composed of a plurality of reinforcing metallic members 3 embedded in concrete 4. Adjacent each end of the tie is provided a pair of openings 5 extending through the tie and spaced apart an appropriate distance to support a rail seat 7 therebetween. The seat 7 comprises a metallic plate having downwardly extending flanges 8 preferably adapted to rest in recesses 9 provided in the sides of the openings 5 for the purpose, although it will be apparent as the invention is better understood that these downturned flanges may merely rest against the walls of the recesses. The width of the rail seat 7 thus provided is preferably materially less than the width of the base 10 of the rail 11, so that the rail may be adjusted, as will be later described, to accurately position it with respect to its companion rail. A sheet of fibrous material 12 is interposed between the base 10 of the rail and the seat member 7 to electrically insulate the rail from this member and from the concrete 4.

The upper portions 13 of the adjacent side walls of the recesses preferably converge as they approach the upper surface of the rail and these portions terminate at their lower edges at an anchor plate 14. This plate, which rail fastening bolts 15 engage, is embedded in the concrete forming the tie and is insulated therefrom by a thick coating 14' of some suitable material preferably an enamel. The lower portions 16 of the adjacent walls of the recesses are disposed inwardly of the upper portions 13.

a substantial distance. Extending downwardly in each recess from an end of the anchor plate 14 and spaced from the adjacent portions 16 is provided a bead or heel 17 behind which a hook 18 of the hook bolt 15 is adapted to engage before the nut or head 19 of the bolt is screwed down to lock the rail firmly in place.

The outer walls of the openings 5 are broken, the lower portion 20 being disposed inwardly of the upper portion to form an offset 21 against which an insulating block or key 22, preferably of wood, may rest and the upper portions 23 of these walls are preferably inclined, as shown. The faces of the keys 22 preferably have an opposite and similar inclination in order to render the whole structure rigid when they are forced down into position. These blocks 20 are of an appropriate length to dispose their tops a substantial distance above the upper surface of the tie. Plates 24 embracing the bolts 15 rest upon the lower flanges 25 of the rail 11 and upon the upper faces 26 of the keys 22 and with the bolts 15 form devices for locking all of the parts in fixed position.

In order that the side thrust of the bolts 15 may not crush the keys 22 when the parts 30 are locked together thrust plates 27 are positioned in suitably formed recesses 28 in the keys 22. Each of these plates is provided with a flat back face 28' and a curved recess 29 adapted to engage the bolt 15.

The fibrous sheet 12 in addition to insulating the base of the rail from the concrete forming the tie performs another important function. This sheet acts as a compensating filling for uniformly distributing the 40 rail load evenly over the entire bearing surfaces between the rail and the tie. As this fibrous material has a lower crushing strength than the concrete it will be crushed away at the high spots and forced into the 45 low spots, thereby causing each unit of area of the bearing surface of the tie to support its share of the rail load. The concrete will sustain a load of approximately 4,000 pounds per square inch. If a load of 40,000 50 pounds be carried by the rail above the tie and if the rail bearing be 5 by 8 inches or 40 inches square the normal or average pressure felt by each square inch of bearing surface will be 1,000 pounds, which is one-fifth the maximum load that the concrete 55 can sustain. The rail base and the seat plate 7 are each comparatively true, but neither is perfectly true. Should it happen that only two points of the metal come in 60 contact with each other, covering say two square inches, then the pressure in the absence of any compensating filling or distributing agent upon each of these two square inches will be one-half the total load or 65 20,000 pounds, which is five times the crush-

ing strength of the concrete. If the sheet 12 of compensating fibrous filler be interposed between the member 7 and the rail the fibrous material interposed between these two one-inch areas will be mashed down and part of it forced to fill in the spots between the remainder of the seat plate and the rail, thus bringing about the desired uniform distribution of the rail load over the entire bearing surface of the tie.

When it is desired to fasten the rail in place by my improved fastener the insulating sheet 12 is placed in position and the rail is next placed upon the insulated seat thus provided and the hooked bolts 15 and keys 22 are positioned. The plates 24 are placed in position and nuts 19 turned down tightly against the plate. If necessary, the rail may be moved sidewise an appreciable distance by cutting away the face of the key at one side and providing a wider key at the other.

It will be apparent from the foregoing that the concrete is completely insulated from the rail and fastening bolts 15 and plates 24 by the sheet 12 on its rail seat, the keys 22 at the sides of the bolt and the enamel surfacing of the anchor plate 14, so that no moisture seeping into the concrete can conduct the current from rail to rail or to the ground either directly or through the reinforcing members incorporated in the concrete. It will be apparent, moreover, that the enameling, should it be found desirable, may be omitted from the portions of the surface of the anchor plate 14 not contacting with the concrete as no loss of current would result were the bolts 15 not insulated from the anchor plate 14 itself so long as the anchor plate is insulated from the body of the tie.

It will be obvious, also, that the fastener thus provided may be cheaply made and may be readily assembled and taken apart, the latter operation requiring only that the nuts 19 be loosened sufficiently to permit the hooks of the bolts to be disengaged from the beads of the anchor plate and turned to engage the lower faces of the keys, as shown in dotted lines 30 in Fig. 1 when a straight upward pull will lift out all the parts.

It is thought that the invention and many of its attendant advantages will be understood from the foregoing without further description and it will be apparent that numerous changes may be made in the form, construction and arrangement of the parts without departing from the spirit and scope of the invention or sacrificing any of its material advantages.

I claim:

1. An insulating rail fastener comprising a tie adapted to support a rail and having an electrically insulated seat for the rail, an electrically insulated anchor disposed be-

- neath said seat, and means engaging said anchor and the rail base to hold the rail in position on said seat.
2. An insulating rail fastener comprising a tie adapted to support a rail and provided with an electrically insulated seat for the rail and with openings at opposite sides of said seat, an electrically insulated anchor disposed beneath said seat, and means engaging said anchor and the rail base to hold the rail in position on said seat.
3. An insulating rail fastener comprising a tie adapted to support a rail and provided with an electrically insulated seat for the rail and with openings at opposite sides of said seat, an electrically insulated metallic anchor disposed beneath said seat and extending between said openings, and means engaging said anchor and the rail base to hold the rail in position on said seat.
4. An insulating rail fastener comprising a tie having an electrically insulated seat for the rail, an anchor disposed beneath said seat and provided with a surface coating of electrically insulating material, and means engaging said rail and anchor for holding the rail to its seat.
5. An insulating rail fastener comprising a tie having an electrically insulated seat for the rail, an anchor disposed beneath said seat and having a heavy coating of enamel, and means engaging said anchor and said rail for holding the rail to its seat.
6. An insulating rail fastener comprising a tie having an electrically insulated seat for the rail and an opening at each side of said seat, an anchor disposed beneath said seat and extending into said openings, said anchor being provided with a surface coating of electrically insulating material, and means engaging said rail and anchor for holding the rail to its seat.
7. An insulating rail fastener comprising a tie having an electrically insulated seat for the rail and an opening at each side of said seat, an anchor disposed beneath the said seat and extending between said openings and having a heavy coating of enamel, and means engaging said anchor and rail for holding the rail to its seat.
8. An insulating rail fastener comprising a tie having an electrically insulated seat for the rail and provided with an opening at a side of said seat, a securing device disposed in said opening and engaging said rail at one end and the tie at the other, the end of the device engaging the tie being electrically insulated therefrom, and an electrically insulating member disposed in said opening with said securing device.
9. An insulating rail fastener comprising a tie having an electrically insulated seat for the rail and provided with an opening on each side of said seat, a device disposed in each opening for holding the rail in position, a metallic anchor electrically insulated from the body of the tie and engaged by both rail-holding devices, and an electrically insulating member disposed in each of said openings for retaining the rail-holding devices in position.
10. An insulating rail fastener comprising a tie having an insulated seat and provided with an opening at a side of said seat, said opening being provided with an offset intermediate its ends, a block disposed in said opening resting upon said offset and extending above said rail, a bolt disposed in said opening and engaging and electrically insulated from said tie, a metallic plate resting on said block and the rail and engaging the head of said bolt for retaining the rail in position.
11. An insulating rail fastener comprising a tie having an electrically insulating seat for the rail and provided with an opening at a side of said seat, a fastening device disposed in said opening and engaging said tie and insulated therefrom, a block disposed in said opening with the fastening device, and a thrust member carried by said block for preventing crushing of the block by the fastening device.
12. An insulating rail fastener comprising a composite tie having an electrically insulated seat for the rail, metal members embedded in the composition forming the tie, and means engaging said metal members and electrically insulated from the composition forming said tie for securing the rail to its seat.
13. An insulated rail fastener comprising a reinforced composite tie provided with a seat for the rail, a fibrous insulating material interposed between said tie and rail having a lower crushing strength than said tie, and means insulated from the tie for holding the rail in position.
14. A rail fastener comprising a composite tie having a seat for the rail, material having a lower crushing strength than said tie interposed between said tie and rail, and means for fastening the rail to the tie.
15. A rail fastener comprising a tie having a seat for the rail and provided with an opening at a side thereof, an anchor member extending into said opening, a securing bolt adapted to engage said anchor, a block disposed in said opening; and a member resting upon said block and base of the rail through which said bolt passes and against which its head engages for holding the rail in position.
16. A rail fastener comprising a tie having a seat for the rail and provided with an opening at the side of said seat, opposite walls of said opening being provided with offsets, a securing bolt disposed through said opening and engaging one of said offsets at its lower end, a block disposed in said

- 4
- opening and resting upon the other offset; and a plate resting upon said block and on the lower flange of a rail and engaged by the head of the bolt.
5. 17. A rail fastener comprising a tie having a seat for the rail and provided with an opening at the side of said seat, a fastening bolt extending into said opening and engaging a side thereof at one end, a block

disposed in the opening and provided with 10 a thrust plate engaging said bolt, and means resting on the block and rail and engaging the said bolt for holding said rail in place.
